UNITED STATES PATENT OFFICE.

SIMON B. HESS, OF NEW YORK, N. Y.

BURGLAR-ALARM SYSTEM.

1,279,344.

Specification of Letters Patent. Patented Sept. 17, 1918.

Application filed June 3, 1915. Serial No. 31,831.

To all whom it may concern:

Be it known that I, SIMON B. HESS, a citizen of the United States, residing in New York city, in the county of New York and 5 State of New York, have invented certain new and useful Improvements in Burglar Alarm Systems, of which the following is a specification.

This invention relates to burglar alarm 10 systems of the class employed for the protection of localized risks, such for example, as bank vaults, stores, lofts, buildings or apartments in residential districts.

Various systems of this class are at present in use, in most of which means are provided whereby an alarm will be started in operation upon interference with the protected structure. The alarm itself is as a rule placed within a housing included in the 20 protective circuit and arranged so as to start the signal in operation upon interference therewith.

Similarly the instruments controlling the protective circuit as well as the alarm circuit in systems of this class are of necessity inclosed within the protected structure.

It is an object of my invention to provide a system simple in construction and economical of installation that will provide 30 novel means to avoid the possibility of defeating the system by tampering with the circuit controlling apparatus, for example, by an unauthorized person who may be concealed within the protected structure and 35 may at an opportune time seek to disconnect the system.

It is another object of my invention to provide a system that cannot be defeated by the men that installed it.

It is still another object of my invention 40 to provide a system so arranged, that when any of the circuit controlling devices or the alarm housing are tampered with while the system is normally set for operation, certain important circuit wires will be ruptured and thereby entirely eliminate the possibility of any person, authorized or unauthorized, from restoring the system to normal, or silencing the signal.

It is still another object of my invention 45 to provide systems wherein the alarm signal will operate continuously until the source of energy is exhausted, upon interference with the circuit controlling apparatus by 55 any person while said apparatus is in its normally set status. In this event the alarm

signal cannot be silenced by any one, even the inventor.

In the embodiment illustrated in the accompanying drawings, Figure 1 is a dia- 60 grammatic view showing the complete system.

Fig. 2 is a perspective view showing part of the main housing which contains the alarm and two of the frame portions of the 65 auxiliary housing for the alarm, in open position with the board broken away to show more clearly the connections to the relay, one of the frame portions being connected to the main housing by a tubular 70 member.

Fig. 3 is a perspective view of one of the frame portions shown in Fig. 2, but looking at the other side of the same.

Fig. 4 is a perspective view of a third 75 frame portion which together with the two frame portions illustrated in Fig. 2 form the complete auxiliary housing.

Fig. 5 is a view of a jack and plug for connecting two portions of a conductor in 80 the tubular member between the main housing and the auxiliary housing of the alarm; Fig. 6 illustrating the plug detached; and Fig. 7 the jack detached.

Fig. 8 illustrates a plug and jack for connecting two circuits, the plug and jack being shown in closed or circuit making position.

Fig. 9 is a fragmental view of the plug 90 detached.

Fig. 10 is a diagram illustrating a system in which the plug and jack shown in Fig. 8 has special application.

In the diagram illustrated in Fig. 1, the heavily indicated wires 11 and 12 and their 95 continuations constitute the protective circuit and are connected to any suitable source of power such as the generator 13, these wires 11 and 12 being connected to the guarded structure understood to be located at A, and 100 passing through the main protective housing and the auxiliary housing of the system.

The main protective signal housing comprises substantially a protected box B in which a signal receiving device or audible 105 alarm is located, and a protected box C in which the controlling mechanism of the audible alarm is located.

The protected box C is connected by a tubular member D with the frame portion E 110 of an auxiliary housing, the auxiliary housing comprising essentially three frame por-

tions, the frame portion E aforementioned and the frame portions F and G, illustrated in Figs. 2, 3 and 4, respectively.

The box B usually embraces a base member 14, on which the audible alarm such as the gong 15 is located. For inclosing the gong there is provided an inner casing 16 adapted to be secured to one side of said base member, preferably leaving a border 17 of said base member 14 free around said inner casing 16. To inclose such casing 16 and secured to said base member, there is provided an outer casing 18 so that before the inner casing 16 in which the gong is located can be opened or destroyed, the outer casing 18 must first be opened.

The box C is constructed somewhat similar to the box B, it embracing a casing 19 closed on top, bottom and three sides, and 20 having an inner door or closing member 20 disposed between the top, bottom and two sides somewhat removed from the outer edges of such top, bottom and two sides, and an outer top or closing member 21 disposed 25 similarly and concealing and protecting the inner door or closure member 20 so that before such inner door can be opened, the outer door 21 must have been opened, the alarm controlling mechanism being disposed in 30 said casing inside said inner door member 20.

The frame portions E, F and G when in closed position are secured to one another face to face with the frame portion F between the frame portions E and G, the arrangement of supporting the several frame portions being such that the frame portions G or F will be the first to be removed, the frame portion E preferably being secured 40 against the wall of a structure.

In practice I find it desirable to place the box B on the outside wall of a protected structure, and the box C directly in the rear of box B on the inside of said wall within 45 the protected structure and provide a section of the usual electric conduit (not shown) to connect the two boxes—said conduit providing a pathway for the circuit wires of the system between the circuit controlling mechanism in box C and the box B, so that all 50 conductors are effectively concealed and protected from mechanical injury and surreptitious tampering.

The wiring is as follows:

55 The main wire 11 beginning at the generator 13, after passing through the guarded structure A passes into the box C through the opening 22 then out through the opening 23 in the box C and thereupon through 60 the opening 24 in the border 17 of the base member 14 to the jack arm 25 which is spaced apart from the jack arm 26 to receive a plug and disposed on one side of the casing 16, the wire 11' connecting the jack arm 26 with the jack arm 27 on the other side

of the casing 16 which jack arm 27 is spaced from the jack arm 28 to receive a second plug, the jack arm 28 being connected by a wire 11^a which passes out through the opening 29 in the border 17 of the base member 70-14 disposed on the same side of the casing 16 as the jack arms 27 and 28 are disposed, thereupon into the box C through the opening 30 and then out again through the opening 31 which is in communication with the 75 conduit or tubular member D illustrated in Fig. 2, and thereafter through several contacts hereinafter to be described to the relay R.

The main wire 12 also beginning with the 80 generator 13 after passing through the guarded structure A passes into the box C through the opening 22, thereupon through an opening 33' in the door member 20 to the jack arm 32 which is spaced from a jack arm 33 to receive a plug, the wire 12^x connected to the jack arm 33 passing through an opening 34 in the door member 20 into the box C and thereupon out through the opening 23 and parallel with the wire 11 through the opening 24 to the jack arm 25' adjacent to the jack arm 25, the jack arm 25' being spaced apart from the jack arm 26' disposed adjacent to the jack arm 26, the wire 12' extending parallel to the wire 11' and connecting the jack arm 26' with the jack arm 27' disposed adjacent to the jack arm 27 which jack arm 27' is spaced apart from the jack arm 28' disposed adjacent to the jack arm 28. Connected to the jack arm 28', 100 there is provided a wire 12^a which extends parallel to the wire 11^a and connects with the relay R after passing through several contacts similar to the wire 11^a. The aforementioned wires 11 and 12 with their continuations when properly connected form a circuit whereby the relay R is energized by the generator 13.

The casing 18 is in the nature of a cover for the casing 16 and is secured to the base member 14 by any suitable means but preferably permitting ready removal. On the inside of the casing 18, there are provided two conductive plugs 35 and 36 properly insulated from the casing 18 and each having an insulated portion 37 in its body portion to form two contacts. The plugs 35 and 36 are disposed to coöperate with the jack arms on the base member 14, the arrangement being such that when the casing 18 110 is in closed position, the plugs will engage the four arms of the jacks so that the wire 11' will permit the passage of current from the wire 11 to the wire 11^a and the wire 12' will permit the passage of current from the wire 12. In Figs. 8 and 9, an enlarged view of the plug 35 and the jack arms coöperating therewith is shown. In the plug 35 there are provided two pairs of recesses 49 and 50, the recesses 49 being disposed on 120

130

one side of the insulated portion 37 and the recesses 50 on the other side of such insulated portion, the recesses of each pair being disposed on opposite sides of the plug 5 so as to form an anchor into which a pair of jack arms may engage. The plug 36 and its co-operating jack arms are identical with the plug 35 and jack arms just described and therefore the description is not 10 repeated.

Somewhat similar to this arrangement is the co-operation of the plug 38 with the jack arms 32 and 33, the plug 38 being fixed to the door member 21 and insulated therefrom, the door member 21 in the present instance being shown as hingedly connected at its lower end to the floor member 39 of the box C, and adapted to be locked at its upper end to the top piece 40. The location of the plug 38 on the door member 21 is such that when the door is closed, the plug will bridge the jack arms 32 and 33 so that the current may pass from the wire 12 to the wire 12^a. From the arrangement 20 of these plugs, it will be seen that when it is attempted to get at the gong or controlling mechanism, the outer member must first be removed which will immediately break the circuit cutting off the current to the relay 25 R and the main cover member will still be locked.

The frame portions E, F and G contain mechanism for setting the alarm, the frame portion F supporting the relay R. The wires 11^a and 12^a, illustrated each as one continuous wire, are provided with several contacts whereby the wires may be interrupted when the frame portions are opened and in turn form continuous passages for the current when the frame portions are closed. To this end, the wire 11^a (Fig. 2) terminates in the contact 41 on the frame portion E, the contact 42 on the frame portion F which is adapted to contact with such contact 41 when the frame portions are closed being connected by a wire 11^b which passes through the frame F (Fig. 3) and terminates in the contact 43. The contact 44 on the frame portion G which is adapted to contact with the contact 43 is connected by the wire 11^c which is secured in a zigzag position to the frame portion G and terminates at its other end in the contact 45 which contact is adapted to contact with the contact 46 on the same side of the frame portion F on which the contact 43 is located, the contact 46 being connected by the wire 11^a passing through the frame portion F to the relay R. The wire 12^a on the other hand terminates in the contact 47 on the frame portion E which is adapted to contact with the contact 48 on the frame portion F which contact 48 is connected by the wire 12^b to the relay R. It will thus be seen that when any one of the frame portions

is displaced, the circuit will be broken and thereby the relay deprived of energy.

There is a circuit provided for energizing the audible alarm and which when connected will prevent the formation of a connection whereby the locking means for the inner casing 16 and the door 20 can be unlocked. 70

The circuit for energizing the audible alarm 15 is as follows: One wire 51 connects the bell magnet 52 with a source of current 53, another wire 54 connects the bell magnet 52 with the contact adjacent to the armature 55 which armature is connected to the source of current 53. When 80 the gong is at rest, the armature 55 is spaced from the contact of the wire 54 and in contact with the contact at the end of a wire 56 which terminates in a contact 57 disposed adjacent to the armature 58 which is normally spaced from such contact 57 and attracted by the relay R when the relay is energized. The armature 58 in turn is connected by a wire 59 with one contact 60 of a switch S. The contact 60 is in contact 90 with the contact 61 of the switch when the alarm is set for operation, the contact 61 being connected by a wire 62 with the wire 51. In the wire 56, there is connected an electromagnet 63 disposed adjacent to the 95 armature 55 and adapted to attract the same when it is energized. Thus when the switch is set so that the contacts 60 and 61 engage one another, and the relay R is deprived of its energy, so that the armature 58 contacts with the contact 57, the electromagnet 63 will be energized, attract the armature 55 and throw it into contact with the contact of the wire 54, whereupon the circuit for the gong 15 is energized. Thus 105 obviously it will be seen that whenever the protected circuit connected to the guarded structure A is broken, or the cover 18 or 21 removed, or any one of the frame portions E, F and G displaced and the relay 110 R thereby deenergized, the audible alarm will be energized.

In addition to the energization of the audible alarm 15, the system will thereby be set so as to prevent the unlocking of the 115 casing 16 and the door 20. The locking means of the casing 16 comprises two brackets 65 secured to the base member 14, having aligned openings and spaced apart to permit a bracket 66 to extend between such brackets 120 65 when the casing 16 is attached to said base member 14, the bracket 66 being secured to such casing 16 and having an opening which aligns with the openings of the brackets 65 when the casing 16 is attached to said base member 14. Secured to one end of the casing 16 is a solenoid 67 which has a core 68 extending through the aligned openings of said brackets 65 and 66 when said solenoid 125 67 is not energized, the core 68 being con- 130

nected to said solenoid 67 so that it cannot be completely detached from said solenoid. Thus, it will be seen that when the casing 16 is attached to the base member 14 and the solenoid is deprived of its energy, the core 68 coöperating with the brackets 65 and 66 will lock said casing to said base member and thus prevent access to the gong 15. The locking means of the door 20 is similar to 10 the locking means just described, two brackets 69 being secured to one of the walls of the box C and spaced apart to permit the bracket 70 to extend between them. The bracket 70 is attached to the door 20. The 15 brackets 69 and 70 are provided with openings which align with one another when the door 20 is closed. The top piece 40 of the casing C is provided with a solenoid 71 having a core 72 connected thereto so that when 20 in suspended position, when the solenoid is not energized, it will extend through the aligned openings of the brackets 69 and 70 and lock the door 20 in closed position.

The winding of solenoid 67 is such that 25 the current of the source of power 53 is not sufficient for its energization and for this reason, it is found desirable to connect the solenoid 67 with a contact indicated by the heavy dot at 73 with which contact 73 30 a public service main may be connected, the other terminal for such circuit being the contact 74 (Fig. 1) illustrated as disposed adjacent to the switch S. The solenoid 67 is connected by a wire 75 with a wire 76 35 which terminates in a contact 77 disposed on the side of the armature 55 which is opposite to that side on which the contact of the wire 54 is located, the contact 77 being adapted to contact with the armature when 40 the gong is at rest. The similar solenoid 71 is likewise connected to a contact 78 adapted to be connected with a public service main and by means of the wire 76 is connected to the contact 77. Disposed adjacent to the 45 contact 61 there is a third contact 79 for the switch S adapted to contact with the contact 61 which contact can take place only when the contact 61 is out of engagement with the contact 60. The contact 79 is connected by 50 the wire 80 with the contact 81 disposed on the same side of the armature 55 as the contact of the wire 54 is disposed and adapted to contact with such armature when the contact of the wire 54 is in contact therewith. 55 There is connected in the wire 80 an electromagnet 82 disposed adjacent to the armature 55 and on the same side as the contact 77. The wire 80 is furthermore connected with the contact 74 already described as adapted 60 to be connected to a public service main.

The switch S is adapted to be operated by a combination lock 83 (Figs. 1, 2 and 3), whereby when the bolt 84 is so thrown that the contact 61 will engage the contact 60, the 65 system is set so that whenever the circuit of

the relay R is disturbed so that the relay R is deprived of energy, the magnet 82 will be energized thereby attracting the armature 55 and forming a circuit to energize the audible alarm 15. Thereupon when the bolt 84 is 70 so thrown that the contact 61 contacts with the contact 79, a circuit will be formed which will energize the magnet 82 and retract the armature into contact with the contact 77 and the contact of the wire 56 thus resetting 75 the armature. Thereupon the bolt 84 can be restored to its first position where it will hold the contact 61 in contact with the contact 60. When the contacts 79 and 61 are in contact, and it is desired to remove the casing 16, it will only be necessary to connect the contacts 73 and 74 with the public service mains, whereupon the solenoid 67 will be energized and withdraw the core 68 from the brackets 65 and 66 and it is then a simple matter to remove the casing 16. On the other hand, if it is desired to open the inner door 20, the outer closing member 21 having been opened, it is only necessary to connect the contacts 78 and 74 with the public service mains and the solenoid 71 will be energized to withdraw the core 72 from engagement with the brackets 69 and 70.

From the foregoing, it will be seen that if an unauthorized person should actually 95 have come into the guarded structure without disturbing the protective circuit at A, before such person could either get at the gong contained in the protected box B or at the controlling mechanism for the gong contained in the protected box C, he would immediately disrupt the circuit when he removed the casing 18 or opened the outer door 21 and furthermore would thereby destroy the unlocking circuit of either the inner casing 16 or the inner door 20.

On the other hand, if the unauthorized person, should contemplate manipulating the combination lock 83, means are provided so that the gong will be energized before 110 such unauthorized person can arrive at the lock, and furthermore the connections for restoring the controlling mechanism to position where the bell will be at rest will be destroyed. To this latter end, as already 115 described, when the frame portion G is removed from the frame portion F, the circuit connected to the relay R will be broken. Obviously, if the gong thereupon started, and the combination lock could be operated 120 to immediately silence it, the alarm might not be prolonged sufficient to attract attention. However, with the present arrangement, as soon as the frame portion G or the frame portion F is removed, the connections for restoring the gong to silence it will be so impaired that such restoration is impossible, the wires 56, 62 and 80 which all three pass through the tubular member D with the wires 11^a and 12^a, or at least the wire 80, 130

will be connected by insulated cores 85 through the frame portion G. Furthermore, the wires 56, 62 and 80, or at least the wire 80, will be drawn taut into the protective box C and fastened in such taut condition in the protected box C, when the frame portions E, F, and G, are secured to one another, and such wires will each comprise two portions, one of which portions is provided 10 with the plug 86 shown in Fig. 6 and the other portion provided with the jack 87 shown in Fig. 7 by means of which the portions are connected to one another and the connected jack and plug arrangements are 15 disposed in the tubular member D remote from handling. From this, it will be seen that when the frame portion G is removed, it will first break the circuit depriving the relay R of energy, thereupon setting the 20 control mechanism to energize the gong 15, and upon further removal of the frame portion G, the wires 56 and 80 or 56, 62 and 80, will be pulled along with it, the jack and plug arrangement easily giving way to such 25 pull. This disruption will, of course, also take place when the frame portion F is removed from the frame portion E, and when the frame portion E is removed from the wall.

30 In Fig. 10, there is shown in diagram a special application for the plug and jack illustrated in Fig. 8. In this diagram, a wire 88 connects a source of current 89 with a resistance 90. The wire 91 connects the resistance 90 with an electromagnet 92, the wire 91, extending parallel to the wire 88 for a considerable distance. A wire 93 connects the electromagnet 92 to electromagnet 94 and a wire 95 connects the electromagnet 40 94 with the source of current 89. At 96 and 97 the plug and jack arrangement of Fig. 8 is disposed, the arrangement being such that when the plug is moved, so that one pair of jack arms comes in contact with its insulated portion, the passage of current will be prevented and thereupon the electromagnets 92 and 94 deprived of their energy. However, at the further removal, so that both 45 pairs of jack arms come in contact with the extreme conductive end of the plug, the resistance 90 will be shunted and thereupon the electromagnet 94 which requires greater magnitude of current to energize it, will be energized, as will electromagnet 92. An 50 audible alarm, such as a bell 98, is connected by a wire 99 with a source of current 100, by a wire 101 with the contact 102 and by the wire 103 with the contact 104. The source of current 100 is connected by a wire 55 105 with an intermediate member 106 to which is pivotally connected the armature 107 adapted to contact with the contact 102. To the intermediate member 106 is also pivotally connected the armature 108 adapted 60 65 to contact with the contact 104. The armature 107 is normally held attracted by the electromagnet 92, breaking the circuit through wire 101. The armature 108 is normally out of contact with the contact 104 and when attracted by the magnet 94 will 70 be brought into contact with contact 104. From the foregoing, it will be seen that the bell 98 will be at rest when the plug is in position where it permits the circuit to pass through the resistance 90 in which case the 75 electromagnet 92 is energized, and that, on the other hand, when in the course of removing the plug from its jack at 96 and 97, should the deenergizing of the magnet 92 not immediately release the armature 107 to 80 contact with the contact 102 and thereby energize the bell 98, the further removal of the plug from the jack will energize the magnet 94 which will thereupon attract the armature 108 into contact with the contact 85 104 where it will be retained and the bell 98 energized by the circuit made through armature 108 and contact 104.

In the accompanying drawings I have diagrammatically represented an embodiment 90 of my invention, but I do not limit myself to the particular arrangement shown, as it will be evident to one skilled in the art, that features of my invention are adapted for use either separately or in combination with 95 each other, and the particular descriptions hereinbefore contained of the typical system shown in the annexed drawings are given for the clearer illustration of my invention. Many changes in construction and 100 arrangement, and insertion or omission of parts may be made without departing from the spirit of my invention.

The casing locking means hereinbefore mentioned is described and claimed in 105 United States Letters Patent No. 1,221,322, dated April 3, 1917, said patent resulting from application Serial No. 147,665, which was a division of this application.

I claim:

1. The combination of an alarm mechanism, inner and outer casings therefor, locking means for said inner casing, releasing means for said locking means, and means controlled by said outer casing for energizing 115 said alarm mechanism and for disabling said releasing means.
2. The combination with a protective circuit, of an alarm mechanism, inner and outer casings therefor, said protective circuit being controlled by said outer casing, locking means for said inner casing, releasing means for said locking means, and disabling means for said releasing means controlled by the protective circuit.
3. The combination with a protective circuit, of an alarm mechanism, inner and outer casings therefor, said protective circuit being controlled by said outer casing, locking means for said inner casing, releasing means

- for said locking means, and means controlled by the protective circuit for energizing said alarm mechanism and for disabling said releasing means.
5. In an alarm system, the combination with a structure to be guarded, said structure having one or more movable portions, of a two wire protective circuit, each wire of said protective circuit being disrupted adjacent to one of said movable portions, a plug connected with said movable portion and adapted to bridge said disruptions to permit the continuous passage of current through said protective circuit when said movable portion is in one position, and adapted when removed, first to cross connect from one wire to the other of said protective circuit, and second to break connection through both wires of said protective circuit, an alarm mechanism, and initiating means for actuating said alarm mechanism controlled by said protective circuit.
5. In an alarm system, the combination with a structure to be guarded, said structure having one or more movable portions, of a two wire protective circuit, each wire of said protective circuit being disrupted adjacent to one of said movable portions, a plug connected with said movable portion and adapted to bridge said disruptions to permit the continuous passage of current through said protective circuit when said movable portion is in one position, and adapted when removed, first to break connection through one wire of said protective circuit, second to cross connect from one wire to the other of said protective circuit, and third to break connection through both wires of said protective circuit, an alarm mechanism, and initiating means for actuating said alarm mechanism controlled by either a break or a cross in said protective circuit.
6. In a burglar alarm, the combination with a structure to be guarded, of a source of current, an alarm mechanism, housing means in which said alarm mechanism is disposed, an outer cover for said housing means, an inner cover for said housing means, the alarm mechanism being disposed inside of said inner cover, wiring connecting said housing means and said guarded structure to said source of current, the wiring being disrupted while passing through said housing means, and a plug on said outer cover adapted to bridge said disruption to permit the continuous passage of current through said wiring when said cover is closed, and initiating means for actuating said alarm mechanism, said initiating means being maintained in inoperative position so long as the current flows through such wiring but assuming operative position whenever said wiring is disrupted.
- 65 7. In a burglar alarm, the combination with a structure to be guarded, of a source of current, an alarm mechanism, housing means in which said alarm mechanism is disposed, an auxiliary casing, setting means for the alarm mechanism disposed in said auxiliary casing, wiring connecting said source of current with said structure to be guarded, said housing means, and said auxiliary casing, initiating means for actuating said alarm mechanism, said initiating means being maintained in inoperative position so long as the current flows through such wiring but assuming operative position whenever said wiring is disrupted, said auxiliary casing comprising three frame portions, wiring passing through all of said three frame portions, contacts on said frame portions contacting with one another when said frame portions are in closed position thereby forming a continuous passage for current through all the wiring of said frame portions so that the current will be broken when any one of said frame portions is displaced, said wiring forming a part of the wiring connected with said source of current, and a locking means disposed on such frame portion which is located intermediate the other two frame portions and operatively connected to said setting means whereby said setting means is operated, the position of such locking means on said intermediate frame portion requiring one of said outer frame portions to be removed before the locking means can be manipulated whereby the wire will be disrupted and energize the alarm mechanism.
8. In a burglar alarm, the combination with a structure to be guarded, of a source of current, an alarm mechanism, housing means in which said alarm mechanism is disposed, a cover for said housing means, an auxiliary casing, setting mechanism for said alarm mechanism, disposed in said auxiliary casing, a wiring connecting said source of current with said structure to be guarded and said housing means, and said auxiliary casing, initiating means for actuating said alarm mechanism, said initiating means being maintained in inoperative position so long as the current flows through such wiring but assuming operative position whenever said wiring is disrupted, electromagnetic locking means associated with said cover and said housing means and adapted when deenergized to lock said cover to said housing means, and a connection from said electromagnetic locking means to a separate source of current, said initiating means when assuming operative position to energize said alarm mechanism opening said connection, said setting mechanism being adapted to be manipulated to close said connection.
9. In a burglar alarm, the combination with a source of current and signaling

means, of a protective circuit including two parallel conductors insulated from each other, there being interposed in each of said parallel conductors, two contact members insulated from each other, a plug adapted to bridge said contact members so as to permit current to flow through said parallel conductors, and signaling means arranged to be shunted when said plug permits the passage of current from one parallel conductor to the other.

Signed at New York city, in the county of New York and State of New York this second day of June A. D. 1915.

SIMON B. HESS.
